UNITED STATES PATENT OFFICE

GEOERGE H. SIMONSON, OF SPRINGFIELD, MASSACHUSETTS, ASSIGNOR TO BIGELOW-SANFORD CARPET CO., INC., OF THOMPSONVILLE, CONNECTICUT, A CORPORATION OF MASSACHUSETTS

MACHINE FOR TRIMMING THE TUFT YARNS OF TUBE FRAMES

Application filed March 27, 1930. Serial No. 439,438.

This invention relates to machines for trimming the tuft yarns projecting from tube frames preparatory to using the tube frames in weaving Axminster carpets and other similar pile fabrics.

In weaving Axminster and moquette carpets and rugs, tuft tube frames are employed to insert the pile loops that are bound to the body fabric, and the different colored yarns for forming the design produced by the pile are drawn into the individual tubes of the tuft tube frames in accordance with a predetermined design.

After the tuft forming yarns have been drawn through the tubes of a tube frame preparatory to using the tube frame in weaving, it is necessary or desirable to trim the tuft yarns so that they will all extend a uniform distance from the tube frame. This trimming operation has been performed heretofore by hand but it is difficult to trim the tuft yarns evenly by the hand method.

One important feature of the present invention therefore resides in a tuft yarn trimming machine having a surface upon which the tuft yarns extending from a tube frame may rest during the trimming operation and also having a cutter and means for holding the yarns clamped upon said surface while they are being trimmed.

Another feature of the present invention resides in a slotted yarn supporting surface and in means for clamping the tuft yarns extending from a tube frame at the opposite side of the slot so that the yarns are firmly held in place while acted upon by a cutter extending in the slot.

A further feature of the present invention resides in a movable support for the tuft yarns and adapted to normally hold the yarns out of the path of a cutter, but constructed to lower the yarns into the path of the cutter, as the clamping means exerts its clamping pressure upon the yarns.

Still a further feature of the invention resides in means movable lengthwise of the yarn supporting table and operable to straighten the yarns out transversely of the table ready to be cut, and in suction means for removing the cut ends from the table.

Other features of the invention and novel combination of parts in addition to the above will be hereinafter described in connection with the accompanying drawings which illustrate one good practical form of the invention.

In the drawings:

Fig. 1 is a top plan view of a tuft yarn trimming machine constructed in accordance with the present invention;

Fig. 2 is a front elevation of the machine of Fig. 1;

Fig. 3 on an enlarged scale is an end view of the machine of Fig. 2;

Fig. 4 is an enlarged elevation of a portion of the rear of the machine of Fig. 2;

Fig. 4^a is a front elevation of stop mechanism to be described;

Fig. 5 is a sectional view taken on the line 5-5 of Fig. 4 and shows the clamp lowered into engagement with the yarns;

Fig. 5^a is a view similar to Fig. 5 but shows the relation of the parts when the clamp is raised; and

Fig. 6 is an enlarged longitudinal sectional view taken on the line 6-6 of Fig. 3.

The trimming machine of the present invention may be used to trim the tuft yarns of tube frames of various constructions. In preparing tuft tube frames for use in connection with a loom to form a pile fabric the yarns 1 used to form the pile are supplied by one or more spools 2 mounted upon the tube frame, and the yarns from these spools are drawn through the individual tubes 3 secured to the carrier bar 4 of the tube frame. The yarns 1 after being drawn through the tubes 3 will present a more or less uneven appearance as shown in Fig. 1. It is therefore desirable to trim these yarns to a uniform length before the tube frames are associated with the loom for weaving pile fabric.

The tuft yarn trimming machine of the present invention may be variously constructed, and as shown in the drawings has the raised platform 5 which is supported at the desired distance from the floor by a supporting frame consisting of the longitudinally extending beams 6 and the supporting legs 7 which are retained in spaced relation to each

other by the transversely extending braces 8.

Upon the platform 5 is mounted the yarn supporting table 9, and the table 9 is supported in elevated relation to the platform 5 by the long angle bar 10 and spaced brackets 10^a having mounted upon their upper edges the U-shaped casting or castings 11 as will be apparent from Fig. 5. In the construction shown the U-shaped casting 11 is provided with the forwardly extending shelf 12 adapted to support the spools 2 of the tube frame during the yarn trimming operation and the tube frame is further supported in this position by the upwardly extending plate 15 13 adapted to engage the tubes 3 of the frame and also constitutes an abutment adapted to be engaged by a vertical wall of the carrier bar 4. The arrangement is such that when the tube frame is placed upon the shelf 12 with a face of the carrier bar 4 abutting against the plate 13 the tube frame will be accurately aligned with the yarn trimming means to be described.

In the construction shown the yarn supporting table 9 is provided with an elongated slot 14 adapted to receive the cutter blade 15 which is advanced longitudinally of the slot to trim the tuft yarns 1. The table 9 in accordance with the present invention is normally supported in a raised position so that its upper or yarn supporting surface will lie above the cutting edge of the blade 15, it being contemplated that the work supporting table will be moved downwardly sufficiently to cause the cutter 15 to act upon the yarns 1 only when the yarns are held clamped upon the table 9 by means to be described.

In the construction shown the vertically movable yarn supporting table consists of the trough shaped bracket or work supporting casing 16, which is mounted within the U-shaped casting 11 for vertical sliding movement through a short distance and the trough 16 is provided adjacent its upper edge with the longitudinally extending bars 17 which are held in spaced relation to each other by the trough 16 to form the slotted yarn supporting table 9. The trough 16 is normally held in its elevated position by the coiled springs 18 which surround the posts 19 and the movement of the trough 16 in an upward direction under the influence of the springs 18 is limited by the rail 20 which is supported in elevated relation to the base of the U-shaped brackets 11 by the posts 19.

As above stated one of the important features of the present invention resides in means for holding the tuft yarns clamped upon the table 9 while the yarns are being acted upon by the trimming knife. This is accomplished in the construction shown by providing the clamp 21 which is normally held in an elevated position above the table 9 but may be lowered by the machine operator into the yarn clamping position. The

construction of the yarn supporting table 9 and cooperating clamp 21 is such that the tuft yarns lying upon the table 9 will normally be held sufficiently elevated to clear the traveling cutter 15 as will be apparent from Fig. 5^a, but when it is desired to trim the yarns 1 the clamp 21 is moved downwardly to hold the yarns 1 firmly in place at the opposite sides of the slot in the work supporting table 9, and as the clamp 21 continues to move downwardly after engaging the table or yarns thereupon it will depress the table from the position in which it is shown in Fig. 5^a to the position in which it is shown in Fig. 5 to thereby bring the row of clamped tuft yarns into position to be severed by the traveling cutter 15.

In the construction shown the clamp 21 is secured to a longitudinally extending bar 22 and this bar is provided at its opposite ends with the posts 23, the lower end portions of which are slidably mounted in sockets 24 formed in the transversely extending webs of the angle bar or frame 10. The vertically sliding posts 23 are normally held in the elevated position in which they are shown in Fig. 3 by the coiled springs 26 that encircle these posts, and the lower ends of which springs rest in pockets formed in the webs 23 while the upper ends of these springs engage sleeves 27 secured upon the posts 23 in the desired position by set screws 28. The clamp 21 is normally held elevated by the springs 26 but may be moved downwardly into engagement with the work through the employment of a foot treadle upon which the machine attendant may stand so that his weight will hold the clamp in firm clamping engagement with the tuft yarns 1 while they are being severed by the traveling knife 15. The means shown for lowering the clamp consists of a foot treadle or rail 29 which extends along the front of the machine and its opposite ends are secured to the supporting levers 30, the rear ends of which are pivotally supported adjacent the rear of the machine at 31. An intermediate portion of each lever 30 is connected by a rod or link 32 to the lower end of a vertically sliding post 23 so that the yarn holding clamp 21 may be lowered into engagement with the work by depressing the pedal 29.

Means for operating the knife 15 to sever the yarns might be variously constructed, but is shown as comprising an endless chain 33 which passes around the sprockets 34, 35 mounted adjacent the opposite ends of the trimming machine. The upper run of the chain 33 rests upon the grooved rail 20 above described as supported by the posts 19. The knife 15 is secured to a block 36 having a post 37 which is connected to a link of the endless chain 33 and the block 36 is constructed to slide in the lower portion of the slot formed between the spaced rails 17 of the table 9.

The arrangement is such that the knife 15 is advanced by the upper and lower runs of the chain 33 and while traveling along the upper run is supported by the rail 20 and is held against lateral displacement by the side rails 17.

The endless chain 33 is driven in the direction indicated by the arrows by an electric motor 38 conveniently mounted below the platform 5 and having a belt 39 adapted to drive a pulley 40 secured to the transversely extending shaft 41 adapted to support and drive the sprocket 34.

It is important that the tuft yarns 1 to be severed be arranged transversely of the table 9 in a straightened condition, and it is therefore desirable to provide means for straightening these yarns transversely of the table. This is accomplished in the construction shown by a rotating brush 42. This brush is not long enough in the construction shown to extend the entire length of the tube frame, the yarns of which are to be trimmed, and the brush is therefore supported in accordance with the present invention for movement lengthwise of the work supporting table. To this end in the construction shown the rotating brush 42 is mounted upon a shaft 43 that is rotatably supported by the horizontally extending plate 44. This plate is shown as secured to the laterally extending portion 45 of the vertically disposed plate 46 that constitutes the travelling carriage for supporting the brush 42 for movement lengthwise of the table. The carriage or vertical plate 46 is shown as provided with the grooved rollers 47 adapted to cooperate with the opposite edges of the carriage supporting rail 48 which rail is secured to and supported by the frame or brackets 10. The brush 42 is driven in the construction shown by a motor 49 mounted upon the horizontally extending plate 44 and power is imparted from the motor 49 to the brush 42 by the belt 50 which passes around the pulleys 51 and 52, provided upon the motor and brush shaft respectively.

It is desirable to provide power driven means for advancing the brush lengthwise of the work supporting table 9 while it is acting upon the tuft yarns 1 and this is accomplished in the construction shown by providing a second endless chain 53 adapted to be supported by sprockets disposed near the opposite ends of the trimming machine, and one of which is driven from the shaft 41. The travelling carriage 46 in accordance with the present invention is provided with chain engaging means adapted to engage the upper run of the chain 53 to move the carriage lengthwise of the trimming machine in one direction and which device is adapted to engage the lower run of the chain 53 to advance this carriage in the opposite direction. The means shown to this end consists of a bolt 54 secured to the plate 46 of the carriage

for vertical sliding movement and the upper end of the bolt 54 is provided with a finger 55 adapted to be engaged with the upper run of the chain 53 while the lower end of the bolt 54 is provided with a similar finger 56 adapted to be engaged with the lower run of the chain 53. It is apparent from the bolt construction just described that if the bolt 54 is moved upwardly into engagement with the upper run of the chain 53 the brush supporting carrier will be advanced lengthwise of the table in a right hand direction, viewing Fig. 2, whereas if the bolt is moved downwardly into engagement with the lower run of the chain 53 the carriage will be advanced lengthwise of the trimming machine in a left hand direction.

It is desirable that means be provided for automatically releasing the bolt 54 from the carriage advancing chain when the carriage reaches either end of its path of travel, and it is also desirable that manually controlled means be provided for moving the bolt 54 into engagement with a run of the chain. This is accomplished in the construction shown by providing a dog 57 near the left hand end of the machine shown in Fig. 2 and constructed to move the bolt 54 upwardly out of engagement with the lower run of the chain 53 as the carriage approaches the left hand end of the machine of Fig. 2, and to this end the bolt 54 is provided with a pin 58 adapted to engage and be raised by the inclined face 59 of the dog 57. A dog 60 is provided at the opposite end of the machine and has the inclined face 61 to disengage the bolt from the upper run of the chain 53 as the carriage approaches the right hand end of the table. The dogs 57 and 60 are supported in their operative position by the brackets 62, 63.

In accordance with the present invention the dogs 57, 60 serve not only to automatically move the bolt 54 to its intermediate or inoperative position but are adapted also to be manually shifted to engage the bolt with the desired run of the chain 53. This is accomplished by pivotally securing each dog 57, 60 to its supporting bracket by a pivot pin 64 and each dog is normally held against a stop 65 by a spring 66. The dog 57 is provided with an operating cable 67 which extends upwardly about a pulley supported by the bracket 62, then downwardly to the foot operated lever or treadle 68 which is pivotally supported for rocking movement by the levers 69. The other dog 60 is connected to the operating treadle 68 by the downwardly extending cable 70 and the foot treadle 68 is normally held in its raised position against the stop 71 by springs or the like 72. The construction just described is such that when the traveling carriage 46 is brought to rest at either end of its path of travel by the engagement of the pin 58 with a dog, the bolt

54 may be manually moved into engagement with the proper run of the chain 53 by stepping on the foot treadle 68 to operate a dog in a direction to shift the bolt from its intermediate position into a chain engaging position. It is desirable to provide means for frictionally holding the dog 54 in its neutral position or in engagement with either run of the chain 53 and this is accomplished by 10 providing the plate spring 73 having a V-shaped portion adapted to engage any one of the three notches 74 formed in a face of the bolt 54.

14 It is desirable to provide means for removing the severed ends of the yarns from the trimming table and this is conveniently accomplished in accordance with the present invention by providing the travel carriage 46 with a suction pipe 75 mounted adjacent 20 an edge of the table 9 as best shown in Fig. 5, and air may be exhausted from the suction pipe 75 by a flexible conduit 76 which may lead to any suitable form of exhaust means. Current for operating the brush driving motor 49 may be supplied by a flexible cable 77 which is conveniently attached to the flexible conduit 76.

It will be seen from the foregoing that the tuft yarns of a tube frame may be evenly 30 trimmed in accordance with the present invention by placing a tube frame upon the shelf 12 so that the carrier bar 4 abuts against the upright 13 with the tuft yarns resting upon the table 9. The tuft yarns may then 35 be arranged in a straightened condition transversely of the table by the rotating brush 42 which is advanced lengthwise of the machine in either direction by manually depressing the foot treadle 68 to shift the bolt 54 into engagement with a run of the endless chain 53. The straightened yarns may then be clamped upon the table 9 by depressing the foot treadle 29 to force the clamp 40 downwardly into engagement with the table 45 9 so that the clamp will firmly hold the yarns in place and will also depress the table 9 sufficiently to bring the clamped tuft yarns 1 into the path of the traveling knife 15 so that these yarns will all be trimmed at a uniform 50 distance from the tube frame. The lower face of the clamp 21 is preferably provided with the central slot 78 adapted to clear the edge of the knife 15.

What is claimed is:—

55 1. In a tuft yarn trimming machine, the combination of a tube frame support, a slotted surface on which the tuft yarns extending beyond the tube frame rest, a brush for straightening out the loose yarn on said supporting surface, a cutter movable along said slot to cut the yarns to a uniform length from the tube frame, and means for holding the yarns while they are being cut.

2. In a tuft yarn trimming machine, the 60 combination of a tube frame support having

a table on which the tuft yarns extending from the tube frame rest, a cutter movable lengthwise of the table, and means for shifting the table to move the yarns resting thereon into and out of the path of the cutter.

3. In a tuft yarn trimming machine, the combination of a tube frame support having a movable table on which the tuft yarns extending from the tube frame rest, a cutter movable lengthwise of the table, and means for clamping the yarns on the table and operable also to shift the table to move the yarns resting thereon into the path of the cutter.

4. In a tuft yarn trimming machine, the combination of a tube frame support having a movable table on which the tuft yarns extending from the tube frame rest, a cutter movable lengthwise of the table, means for normally holding the table in a position to cause the moving cutter to clear the yarns upon the table, and means for clamping the yarns on the table and operable also to shift the table to move the yarns thereon into the path of the cutter.

5. In a tuft yarn trimming machine, the combination of a tube frame support having a table on which the tuft yarns extending from the tube frame rest, a cutter movable lengthwise of the table in non-cutting relation with the yarns on the table, and means for relatively moving the table and cutter in a direction to cause the traveling cutter to sever the yarns on the table.

6. In a tuft yarn trimming machine, the combination of a tube frame support, means for positioning the tube frame on the support that the tubes may extend a uniform distance from the support, a table on which the loose tuft yarns extending from the tube frame rest, spring means for normally supporting the table in raised position, a normally elevated clamp, means for depressing the clamp to lower the table and hold the yarns in place upon the table, and a cutter below the clamp for severing the yarns while they are held by the clamp.

7. In a tuft yarn trimming machine, the combination of a tube frame support, a slotted table at one side thereof on which the tuft yarns extending from the tube frame rest, springs normally acting to elevate the table with the tuft yarns thereon, a cutter normally disposed below the slot in the table and provided with power actuated means for advancing the cutter along said slot, a clamp above the table, and means for depressing the clamp to hold the yarns across said slot and to depress the table that the cutter may enter the slot in the table to cut the yarns.

8. In a tuft yarn trimming machine, the combination of a tube frame support having a table on which the tuft yarns extending from the tube frame rest, means for arranging the yarns in a straightened condition upon the table, a clamp for holding the yarn

in the straightened condition upon the table, and a cutter for severing the clamped yarns.

9. In a tuft yarn trimming machine, the combination of a tube frame support having a table on which the tuft yarns extending from the tube frame rest, means mounted for movement lengthwise of the table and adapted to lay the yarns in a straightened condition upon the table, and a cutter for severing the yarns resting upon the table.

10. In a tuft yarn trimming machine, the combination of a tube frame support having a table on which the tuft yarns extending from the tube frame rest, a rotating brush for laying the yarns transversely of the table, power means for advancing the brush along the table, and a cutter for severing the yarns resting upon the table.

11. In a tuft yarn trimming machine, the combination of a tube frame support having a table on which the tuft yarns extending from the tube frame rest, a carriage mounted for movement longitudinally of the table and provided with means for straightening the yarns across the table, power means for advancing the carriage in either direction along the table, and a cutter for severing the yarns resting upon the table.

12. In a tuft yarn trimming machine, the combination of a tube frame support having a table on which the tuft yarns extending from the tube frame rest, a tuft yarn trimmer movable along the table for trimming the yarns upon said table, and suction means movable with the trimmer for removing the ends as they are trimmed from the yarns.

13. In a tuft yarn trimming machine, the combination of a tube frame support having a table on which the tuft yarns extending from the tube frame rest, means for holding the tuft yarns clamped upon the table during the trimming operation, a tuft yarn trimmer movable along the table for trimming the yarns while held clamped, and suction means movable with the trimmer for removing the trimmed ends from the table as they are progressively cut.

14. In a tuft yarn trimming machine, the combination of a tube frame support having a slotted and yieldingly supported trimming table on which the loose tuft yarns extending from the tube frame rest, clamping means for holding the tuft yarns clamped upon the table and across said slot, a knife normally positioned below the slot in the table, means for depressing the clamping means to clamp the yarns and depress the table that the knife may enter the slot, and an endless operating member for the knife to cut the yarns extending across the slot.

15. In a tuft yarn trimming machine, the combination of a tube frame support having a trimming table on which the tuft yarns extending from the tube frame rest, means for laying the yarns transversely of the table

including a carriage mounted to travel along the table and provided with a rotating brush that engages the yarns, mechanism for reciprocating the carriage including an endless chain and means upon the carriage engageable with one run of the chain to advance the carriage in one direction and engageable with the other run of the chain to advance the carriage in the opposite direction, and a cutter for severing the yarns.

16. In a machine for trimming tuft yarns which extend from the tubes of a tube frame that the individual yarns may be trimmed to the same length, comprising, in combination, a tube frame support, a table extending at one side of said support and on which the separate tuft yarns rest when the tube frame is positioned on its support, means for aligning the tube frame on its support that the tubes of the frame may extend the same distance towards the table, a cutter movable longitudinally of the table, and means for relatively shifting the table and cutter in a direction transversely of the tuft yarns to present the yarns on the table into and out of the path of the cutter.

17. In a machine for trimming tuft yarns which extend from the tubes of a tube frame that the individual yarns may be trimmed to the same length from the ends of the tubes, comprising, in combination, a tube frame support, a yieldingly mounted table extending at one side of said support and on which the separate tuft yarns rest when the tube frame is positioned on its support, said table having a cutter slot, a cutter normally below said slot, a clamp for the tuft yarns, and means for depressing the clamp upon the yarns and depressing the table that the cutter may extend upwardly through the slot in the table to cut the yarns.

In testimony whereof, I have signed my name to this specification.

GEORGE H. SIMONSON.
